UNITED STATES PATENT OFFICE.

HENRY A. WISE WOOD, OF NEW YORK, N. Y., ASSIGNEE, BY MESNE ASSIGNMENTS, TO
WOOD NEWSPAPER MACHINERY CORPORATION, OF NEW YORK, N. Y., A CORPORA-
TION OF VIRGINIA.

APPARATUS FOR DELIVERING FOLDED SHEETS.

1,266,742.

Specification of Letters Patent. Patented May 21, 1918.

Application filed June 16, 1918, Serial No. 773,918. Renewed December 10, 1917. Serial No. 206,544.

To all whom it may concern:

Be it known that I, HENRY A. WISE WOOD, a citizen of the United States, residing at New York, in the county of New York and 5 State of New York, have invented a new and useful Apparatus for Delivering Folded Sheets, of which the following is a specification.

This invention relates to the delivery of 10 folded sheets from the folding mechanism of a web printing press.

The principal object of the invention is to provide for delivering the sheets by an apparatus, by which the uniform delivery 15 of the sheets without buckling or crumpling will be assured, and by which the speed of delivery can be materially increased.

For the purpose of securing this result the paper as it comes from the folding rolls 20 is given a curve at the end of such a nature that longitudinal buckling is prevented and that when the front end strikes the fan blade it will be capable of springing or yielding to prevent both longitudinal and 25 lateral buckling of the front end.

Reference is to be had to the accompanying drawings, in which—

Figure 1 is an elevation of a fan delivery 30 constructed in accordance with this invention; and

Fig. 2 is a similar view showing the parts in other positions.

So far as I am aware, folded sheets are delivered in pairs at the present time from 35 rotary folders in a straight form. Therefore, the straight bundle of sheets striking the fan blade have a tendency to buckle between the fans during delivery, and the higher the speed the greater the difficulty.

40 This invention is made for the purpose of securing a more uniform delivered product and especially to provide for doing it at a high rate of speed so that the speed of the folder can be materially increased.

45 The invention is shown as arranged for taking folded bundles of sheets from a pair of folding rolls 10. Instead of the usual straight paper guide a guide 11 is mounted on a stationary support 12 and provided 50 with an upper concave curvature at 11^a, and a lower convex curvature 11^b on the operative side, thus being of an ogee or S shape. The usual rotary fan 12^a having curved blades 13 is provided. This is located in

such position that as the blades swing over 55 into place for receiving the advance end of the bundle of sheets they cross the line of the guide at a point near that at which the curvature changes from concave to convex. The usual stop 14 is provided mounted on a 60 support 15 on the frame and the papers are delivered to delivery belts 16 or the like.

The method of delivery carried out by this apparatus is as follows:—The folded sheets coming down through the rolls 10 at 65 an inclination with the folded end forward strike the concave surface 11^a. Thus they are given a downward curve at the end uniform all the way across the bundle. As the bundle of sheets drops down the guide 11 70 this end curvature is maintained until the end of the bundle of sheets strikes a fan blade. The formation of this curvature is indicated in the position A of Fig. 1 while the next result of it is indicated in position 75 B in Fig. 2. In this latter position the curved bundle of sheets is just passing from the concave to the convex portion of the guide. The curvature of the sheets at the end is maintained until the sheets strike the 80 fan blade 13 which then just comes into proper position to receive the sheets. The result at this point is important. With the bundle of sheets arranged in a plane, the sudden striking of the end thereof against 85 the fan blade would have a tendency to buckle the sheets longitudinally at a point near the advance end, and ordinarily there is no way of controlling this. But on account of the preliminary curve which has been given 90 to the bundle of sheets and which is maintained, as described herein, this curved end is unsupported at both edges when it strikes the fan blade. This causes the fan blade immediately to turn this advanced end 95 reversely all the way across as indicated by the arrow in Fig. 2. In this way longitudinal crumpling is eliminated and all the bundles of sheets are affected in the same way and a uniform product is secured.

It 100 is to be understood, of course, that the fan blades rotate more slowly than the speed of the bundle of sheets down the guide, as is usually the case. Thus the speed of the sheets is retarded by the fan blade at the 105 same time that the curvature is changed. By this method also it will be seen that the blades of the fan take the bundle of sheets

along the convex surface of the guide throughout the remainder of the travel thereof with the blades. Two other positions of the bundle are shown at C and D 5 in Figs. 1 and 2 respectively. At the bottom the bundles strike the stops in the usual way and the sheets are deposited on the delivery belts. The method of delivering herein set forth is not claimed in this 10 patent as it has been made the subject of my divisional application filed December 3, 1917 on a method of delivering folded sheets, Serial No. 205,136.

Although I have illustrated and described 15 only one application of the invention, I am aware of the fact that many modifications can be made therein by any person skilled in the art without departing from the scope of the invention as expressed in the claims. 20 Therefore, I do not wish to be limited in these respects, but what I do claim is:—

1. In an apparatus for delivering folded sheets, the combination of a pair of folding rolls effective to deliver folded sheets at an 25 inclination, a substantially vertical curved paper guide having a concave surface facing the edges of the sheets thus delivered and effective to curve said sheets and a convex curve in position to reverse the inclination of their line of travel, and a rotary fan 30 to receive the sheets from said curved guide.

2. In a device for delivering folded sheets, the combination with folding rolls, of a 35 guide having a concave curve in position for receiving the ends of the sheets from the rolls and curving them, and a convex curve below the same and continuous therewith, a rotary fan having blades movable forwardly along the convex curve for receiving the 40 ends of the sheets and keeping them in contact with said convex curve, and a stationary stop located at the bottom of said guide for receiving the ends of the sheets as they are dropped from the blades, the blades being located to withdraw past the guide before the sheets engage the stop.

3. In an apparatus for delivering folded 50 sheets, the combination of a pair of folding rolls, a curved paper guide having a concave surface facing the edges of the sheets thus delivered and effective to curve said sheets and a convex curve, and a rotary fan in position to receive the ends of the sheets

from the concave part of said curved guide and reverse their curvatures along said concave curve to prevent their buckling or crumpling. 55

4. In an apparatus for delivering folded sheets, the combination of a pair of folding rolls effective to deliver folded sheets, a 60 curved paper guide having a concave surface facing the edges of the sheets thus delivered and effective to curve said sheets, and a rotary fan in position to receive the ends of the sheets from said curved guide 65 while in the curved shape caused thereby and reverse their curvature to prevent their buckling or crumpling.

5. In a sheet folding and delivering mechanism, a pair of folding rolls and a rotary 70 sheet laying fan, in combination with means for causing the sheet to assume an S-shaped curve during its transmission from the folding rolls to the point of delivery.

6. In a sheet folding and delivering mechanism, a pair of folding rolls and a rotary sheet laying fan, in combination with means for so maintaining the curvature of the sheet at all points between the folding rolls and the point of delivery to the fan that the 80 moving sheet will resist the tendency to buckle in the direction of its line of travel. 75

7. In a sheet delivery apparatus, the combination with a concave guide adapted to receive the advancing end of a sheet and 85 curve the same into a concave form, of a rotary fan located in position to receive the advance end while maintained in such concave form and immediately reverse its curvature. 90

8. In a sheet delivery, the combination with a guide adapted to receive the forward end of an advancing sheet and bend it into 95 curved form at the end, the curve being uniform across the sheet, of a rotary fan located in position to receive said end while so curved and prevent its assuming a flat shape.

In testimony whereof I have hereunto set my hand, in the presence of two subscribing 100 witnesses.

HENRY A. WISE WOOD.
